UNITED STATES PATENT OFFICE.

ALCORN RECTOR, OF HOT SPRINGS, ARKANSAS, ASSIGNOR TO WILLIAM SOMERVILLE, OF ST. LOUIS, MISSOURI.

GAS-LAMP.

SPECIFICATION forming part of Letters Patent No. 678,513, dated July 16, 1901.

Application filed November 17, 1899. Serial No. 737,282. (No model.)

To all whom it may concern:

Be it known that I, ALCORN RECTOR, a citizen of the United States, residing at Hot Springs, in the county of Garland and State 5 of Arkansas, have invented certain new and useful Improvements in Gas-Lamps, of which the following is a specification.

My invention relates to vapor-burning lamps; and it consists in the novel construction and arrangement of its parts, as herein-after set out in this specification and the claims thereto attached.

The accompanying drawing is an elevation of my invention, partly in section and partly 15 in perspective.

My invention is described as follows:

The lamp complete consists of a reservoir 1, and running from each end of the reservoir and extending upwardly from one end of said 20 reservoir is a supporting-pipe 2, and from the other end is a supporting-arm 6. The supporting-pipe on the left-hand side is hollow its entire length, and at its lower end and connected with its hollow is a pipe 4, that runs 25 down to the bottom of the reservoir, and around its lower end is a network 5 to prevent matter that may be deposited in the bottom of the reservoir from entering the pipe. On the other side of the reservoir the 30 arm 6 runs up a short distance. Resting on the upper end of said arm 6 is a mixing-tube 3, its upper end turning at right angles to the left. This mixing-tube is hollow all the way down and has a hollow branch mixing-tube 7, 35 that runs inwardly to a point over the center of the reservoir. Connected with this branch mixing-tube 7 is an extension 8 of said mixing-tube that runs upwardly, having in its upper end a burner 9. Around the extension 40 8 and near the upper end thereof is secured a framework 10, and in this framework is a wire 11, which holds the mantle 12. This framework also holds the chimney 13. At the upper end of the supporting-pipe 2 is a 45 lighting-valve 14, and connected therewith is a generator 25, having at its right-hand end a gas-tip 15, which runs into a cup 16, and immediately to the right of this cup is an air-regulator 17, both connected to the right-angle 50 bend of the mixing-tube 3, the air passing

through the openings in said regulator and through like openings in the left bend of arm 3, said regulator adapted to be turned on said pipe, and thereby regulate the inlet of air.

Running from the upper part of the reservoir 1 is a pipe 18, which opens into the reservoir. This pipe enters into another pipe 20, which has two parts, the part 21 turning inwardly and upwardly until it comes against the upper end of the extension 8 and is provided with a gas-tip 22 and is in position for the light that may pass out through its tip to light the gas that may pass out through burner 9 under the mantle 12. The part 23 of the pipe 20 runs up by the side of the supporting-pipe 2, its end 24 provided with a gas-tip 24' and turning inwardly under the generator 25 in position to throw the flame that issues from its burner around said generator. In the pipe 18 and between reservoir 1 and 70 pipe 20 is a valve 26.

On the top and right-hand end of the reservoir is a filler-plug 27, and in the end of this filler-plug is an air-valve 28, and running from the filler-plug to the bottom of the reservoir is a pipe 18', its lower end surrounded by a wire net 9' to separate and distribute the air through the gasoline as it is forced down through said pipe, thus carbureting the air and causing a sufficient quantity of it to 80 mix with the oil and to pass out through pipes 18, 20, 21, and 24, when the valve 16 is turned without being heated.

This lamp is operated as follows: Firmly close the lighting-valve 14, unscrew the filler-plug 27, fill the tank up even with the lower edge of the filler-hole, take an air-pump, attach it to the air-valve, pump in air to give sufficient pressure, then screw down the air-valve tight and take off the pump. Now open 90 the valve 26 and light the escaping gas at 24'. This immediately throws a flame around the generator 25. Then light the gas at 22 and turn on valve 14. The gas immediately passes through needle 15, down mixing-tubes 3 7 8, 95 through burner 9, and is lighted by the flame that issues from the tip 22 without making a noise. Then turn off valve 26, which will stop the flow of gas from points 22 and 24, and the heat from the chimney 13 will keep the gen- 100

erator sufficiently warm to vaporize the gasoline.

While I have shown the pipes 18 and 20 and branches as attached to a lamp, as shown, yet it is true that these auxiliary pipes may be adapted and applied to any lamp constructed substantially as the one shown, even though the reservoir may be above the lamp, or may be at the side, or even in the basement of a house. In this last case pipe 18 would only have to be sufficiently long to reach from the reservoir to the lamp.

Having described my invention, what I claim as new, and desire to secure by Letters 15 Patent, is—

1. In an incandescent vapor-burning lamp, having a reservoir, a vaporizer, and a mixing-tube, the combination of a branched pipe extending from the upper part of the reservoir above the surface of the hydrocarbon therein, one branch terminating adjacent the vaporizer, the other branch terminating under the mantle, substantially as shown and described and for the purpose set forth.

25 2. An incandescent vapor-burning lamp, consisting of a reservoir, having a supporting-pipe 2, and a supporting-arm 6; a supply-pipe 4 within the supporting-pipe; a vaporizer 25; a mixing-tube 3, supported on said 30 supporting-arm 6; a burner 9, on the end of said mixing-tube 3, and a branched pipe 20, extending from the upper part of the reservoir, above the surface of the hydrocarbon therein, one branch terminating adjacent the 35 vaporizer, the other terminating under the

mantle, substantially as shown and described and for the purposes set forth.

3. An incandescent vapor-burning lamp, consisting of a reservoir 1, having a supporting-pipe 2, extending upwardly from one end 40 of the reservoir; a supporting-arm 6, extending upwardly from the other end of the reservoir; a supply-pipe 4, within the supporting-pipe, and passing to the bottom of the reservoir; a vaporizer 25, connected with the 45 upper end of supporting-pipe 2; a supporting-arm 6, extending upwardly, a short distance from the other end of the reservoir; a mixing-tube 3, resting on said supporting-arm; a burner 9, on the lower end of said mixing-tube; an air-regulator 17, on the upper 50 end of said mixing-tube; a branch pipe 20, extending from the upper part of the reservoir, above the surface of the hydrocarbon therein, one branch terminating adjacent to 55 the vaporizer, the other terminating under the mantle; a filler-plug 27, in the top of the reservoir; an air-valve 28, in said plug; a pipe 18', connected with said air-valve, and passing down in and to the bottom of the reservoir; and 60 a wire net 9', surrounding the lower end of the last-mentioned pipe, substantially as shown and described and for the purposes set forth.

In testimony whereof I affix my signature in presence of two witnesses.

ALCORN RECTOR.
